NECKTIE PRESSING MACHINE

Joseph T. Jordan, Lugoff, S. C.

Application September 5, 1939, Serial No. 293,491

2 Claims. (Cl. 38—71)

This invention relates to pressing machines, and its general object is to provide a machine that is primarily designed for pressing neckties of the four-in-hand type, in a manner to restore the same to their original shape and a new like appearance, in that the machine is capable of applying ample pressure and heat to the tie and a shaping element is provided for the latter.

A further object is to provide an electric pressing machine for a necktie that can be operated with minimum effort on the part of the user and is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a top plan view of the necktie pressing machine which forms the subject matter of the present invention.

Figure 2 is a side elevation thereof, with parts in section.

Figure 3 is an end view.

Figure 4 is a top plan view of the shaping element for disposal within a tie.

Referring to the drawing in detail, it will be noted that my machine includes a pair of yokes 1 and 2 of substantially U-shaped formation, opening laterally toward the front of the machine to provide superimposed upper and lower arms 3 and 4. The yokes are disposed in spaced parallel relation with respect to each other, and in fact provide the end members for the machine.

Bridging the lower arms and secured thereto in any appropriate manner, is a base plate 5 provided with a marginal flange 6 rolled in channel formation and disposed in clamping engagement

with the marginal edge portion of a cover sheet 7 for a pad 8 of felt or the like, mounted on the base plate 5, as best shown in Figure 2, with the result it will be seen that the pad and cover therefor provide a pliable support for the tie during the pressing action, as will be apparent.

Engageable with the underside of the upper arms and bridging the same, is a heating unit 9 of the same width and length as that of the tie support and includes a housing that has mounted therein an electric heating unit 10 that is sup-

plied with current through the medium of a conductor 11 connected thereto at one end, while its opposite end is connected to a pronged socket member 12 secured to the yoke 2 and for the purpose of receiving a companion member 13 of the usual electric cord 14.

The yoke 2 has formed thereon and extending inwardly from the upper arm thereof a pair of spaced parallel ears 15 providing bearings for a pivot pin 16 secured to and extending through one end of a pressing lever 17, the latter being relatively wide and of a length to extend from the yoke 2 to the yoke 1, as well as to overlie the latter, as best shown in Figure 2. The free end of the pressing lever 17 is upwardly flared to provide ample hand gripping means 18 to facilitate the application of pressure to the lever.

The heating unit is carried by the pressing lever and for that purpose there is secured to and rising from the unit, a substantially U-shaped bracket 19 having its arms reduced toward their upper ends with a mounting pin 20 extending through said ends, and secured in the down-turned flanges extending along the longitudinal edges of the lever, as best shown in Figure 3, which likewise illustrates that the flanges extend about the free end of the lever, so as to eliminate sharp edges about the hand gripping means.

In order to hold the heating unit normally elevated above the tie support, I provide a spring plate 21 secured to the undersurface of the lever 17 and shaped to provide leaf like spring arms 22 having their free ends bearing against the inner wall of the upper arm 3 of the yoke 2, as shown in Figures 1 and 2.

From the above description and disclosure in the drawing, it will be obvious that when pressure is applied to the hand gripping means 18 of the pressing lever 17, that the heating unit is forced downwardly against the action of the spring arms 22, for disposal in pressing association with respect to the tie support, for pressing a tie resting on the latter, and when the heating unit is disposed in its elevated position, ample space is provided for placing a tie on the support, as will be apparent upon inspection of Figure 2.

A shaping element 23 such as shown in Figure 4 is provided for the tie and is inserted in the folds thereof before the tie is placed on the support, the element being in the form of a blade formed from any material suitable for the purpose and is tapered toward one end to conform to the shape of the tie, while its wide end is preferably rounded as shown. The element 23 is made into

several sizes for shaping ties of various widths, and two elements are preferably used for pressing a tie, one for the wide end portion thereof, and the other for the narrow end portion. The 5 shaping elements may have an opening therein adjacent one of their ends, for receiving a nail or the like for suspending the same therefrom when not in use.

It is thought from the foregoing description 10 that the advantages and novel features of the invention will be readily apparent.

It is to be understood that changes may be made in the construction and in the combination and arrangement of the several parts, provided that such changes fall within the scope 15 of the appended claims.

What I claim is:

1. A pressing machine comprising spaced 20 yokes providing the ends of the machine and opening toward the front thereof to provide upper and lower arms, a base plate secured to and bridging the lower arms, a pad mounted on the plate, a cover for the pad, a marginal flange about the base plate and disposed in clamping 25 engagement with the marginal edge portion of the cover for securing the pad to the base plate, said pad and cover providing a pliable support for articles to be pressed, an electric heating unit movable between the upper arms and the sup-

port for cooperation with the latter for pressing articles, a hand lever pivotally connected at one end to the upper arm of one of said yokes, means rising from the heating unit and having the lever pivotally connected between its ends thereto for carrying the unit and spring means secured to the lever and engaged with the latter arm for normally holding the unit elevated above the support. 5

2. A pressing machine for four-in-hand ties, 10 comprising spaced yokes providing the ends of the machine and opening toward the front thereof to provide superimposed upper and lower arms, a pliable support for receiving a tie to be pressed and secured to and bridging the lower 15 arms, an electric heating unit movable between the upper arms and the pliable support and co-operating with the latter for pressing a tie, ears formed on the upper arm of one of said yokes, a hand lever having one end pivoted to the ears, 20 a mounting bracket secured to and rising from the heating unit and having the lever pivotally connected between its ends thereto for carrying the unit, and spring means secured to the underside of said lever and including spring arms 25 engaged with the latter yoke for normally holding the unit elevated above the support.
